UNITED STATES PATENT OFFICE.

WILLIAM E. SAWYER AND WILLIAM SAWYER, OF NEW YORK, N. Y., AS
SIGNORS TO EASTERN ELECTRIC MANUFACTURING COMPANY, OF MID-
DLETOWN, CONNECTICUT.

ELECTRIC-LIGHTING SWITCH.

SPECIFICATION forming part of Letters Patent No. 235,460, dated December 14, 1880.

Application filed October 6, 1880. (No model.)

To all whom it may concern:

Be it known that we, WILLIAM E. SAWYER and WILLIAM SAWYER, citizens of the United States, residing at New York, in the county 5 of New York and State of New York, have invented certain new and useful Improvements in Electric - Lighting Switches; and we do hereby declare the following to be a full, clear, and exact description of the invention, such 10 as will enable others skilled in the art to which it appertains to make and use the same, reference being had to the accompanying drawings, and to letters or figures of reference marked thereon, which form a part of this 15 specification.

Our invention relates to electric - lighting switches; and it consists in a system of contacts and levers actuated by a cam or suitable mechanism operating to light the lamp or 20 lamps, either partly or wholly, by instantly turning on a part or the whole of the current without intermediate graduations.

It further consists in a system of levers actuated by suitable mechanism to turn on part 25 of the current when one of the levers is moved in one direction, and to turn on the whole current to the system when the lever is moved in the opposite direction.

It further consists in a series of levers and 30 contacts so arranged that no current will be directed to the lighting system when the actuating mechanism is at an intermediate point between the levers.

It further consists in details of construction 35 that will be hereinafter more fully set forth in the accompanying specification, and pointed out in the drawings, in which—

Figures 1, 2, 3, and 4 are plan views, partly 40 in section, of the switch mechanism, lamps, and circuits.

Heretofore it has been considered necessary to turn on the electric current gradually to an incandescent lamp. It has been found, however, that such is not necessarily the case. 45 Moreover, by turning on the current gradually there is a loss of time that is objectionable.

The object of our invention here presented is to enable us not only to graduate the light

as may be desired, but to graduate it instantly 50 and in a simpler manner than has heretofore been done.

Referring more particularly to the drawings, A A' A² are levers pivoted as shown. To the lever A² is secured a projection, F, that 55 may constitute a part of the lever A². An insulating-piece, B, is also fastened to lever A², in order to insulate a spiral compression-spring, C, which reacts both upon lever A² and A'. The upward movement of lever A' is 60 limited by a suitable stop pin or piece, D. The lever A' is further provided with a projection, E, by which contact between levers A and A' is made.

G is a cam-shaped finger-piece, suitably pivoted, as shown in the several figures. The 65 circuits are represented at I J K K L.

The lever A has attached to it a compression-spring, M, which serves to force the lever downward into contact with an insulated 70 piece, b, on one of the projections of lever A², the end of the lever A playing between the projections a b of said lever A². (Vide Figs. 1, 2, and 3.)

In the position shown in Fig. 1 the cam G 75 is in contact with lever 13, thus bringing lever A into contact with the projection E of lever A', and at the same time with the end a of lever A², and just raised from contact with stop D; nor is the lever A' in contact with 80 stop D. Here the circuit, Fig. 1, is from + to L lamp and to — point; also from + to A, E, A', H, I, and J to —; also from + to A, A², G, K, and J to —. The result is that the lamp 85 is short-circuited by the last mentioned, (A A² G K J,) and none or but very little of the current goes through the lamp. Now suppose we turn the cam G in the direction of the arrow, and the following arrangement ensues: All the contacts are in the same position as before, excepting the contact of cam G, and that the lever A now rests on stop D. The circuits are now from + to L to lamp and to —; from + to A, E, A', H, I, and J to —. The result 90 is that the current is equally divided, one-half 95 going through the lamp, and a proportionate amount of light is obtained. Now to turn the whole current into the lamp the cam G is

5 moved in the reversed direction, as indicated in Fig. 3. Here cam G is in contact with lever A², the insulated pin b being in contact with lever A to raise the latter, lever A' being in contact with stop-pin D, but not with lever A, and the circuit is as follows: From + to L through the lamp and to —, all of the current going through the lamp.

10 We may introduce a magnet into the circuit, placing the armature on the lever A, as indicated in Fig. 4. Suppose the cam G to be turned as indicated in Figs. 2 and 4, the lever A is in contact with stop-pin D and with ends E and a of levers A' and A², the cam G being out of contact with lever A² and lever A' out of contact with stop D. The circuit is as follows: From + to A coils of magnet Y L and lamp to —, and from + A, E, A', H, I and J to —. The result is, as before, that one- 15 half of the current goes through the lamp, as the contact-point a of lever A² prevents the magnet from raising the armature X on lever A. Now, if we move the cam G to the third position, the circuit will be from + to lever A, coils of magnet Y L, and lamp to —; and from + to A, E, A', H, L, and J to —; but as the 20 contact-point a of lever A² is now raised so high as to clear lever A, and the magnet Y acts to raise the armature-lever A from E, which can- 25 not follow, owing to the stop-pin D, and thus the latter circuit is broken and all of the current goes through the lamp; but should the lamp-circuit be interrupted by any accident the magnet Y becomes demagnetized and the 30 lever A drops to contact with E, thus main- 35 taining a circuit by way of + to A, E, A', H, I and J to —. Thus it will be seen that by simply turning the cam or other lever-actuating device in the proper direction, as indicated and explained, the current flowing to a lamp or lighting system can not only be 40 graduated as desired, but such graduation will be effected instantly, or the whole current

45 can be passed through a lamp or lighting system in the same manner without turning on the current gradually, as is now the case.

We do not confine ourselves to any particular resistance as respects the resistance in the lamp, as it is obvious that we may employ several levers or other suitable devices in connection with the lamp in case we desire to make more graduations of the light than is deemed necessary or accomplished in the present instance.

Having thus described our invention, what 55 we claim, and desire to secure by Letters Patent, is—

1. An electric-lamp-lighting switch consisting of a system of levers actuated by a cam or other suitable mechanism, whereby the current is caused to pass wholly through the lamp, or partly through the lamp, and a resistance introduced into the circuit by the lever-actuating mechanism, substantially as described. 60

2. An electric-lamp-lighting switch consisting of a system of levers, one of which is caused to make contact with one or all of the series of levers and with a stop-piece in such manner as to instantly regulate the quantity of current required to flow to the lamp or lighting system, substantially as described. 65

3. In an electric-lamp-lighting switch, the combination, with a cam and system of levers, as described, one of the levers being provided with an armature, of an electro-magnet in the 70 main circuit, whereby a part or the whole of the current is caused to flow to the lamp, substantially as described. 75

In testimony whereof we affix our signatures in presence of two witnesses.
